UNITED STATES PATENT OFFICE.

VINCENT WAITKUS, OF BALTIMORE, MARYLAND.

YARN CLEANER.

Application filed May 11, 1923. Serial No. 633,365.

This invention relates to means for cleaning yarn, the object of the invention being to provide a device for smoothing and polishing the yarn on all sides by removing therefrom slubs, bunches, seed shells, sand, dirt and other foreign matter and bad spots without in any way weakening the yarn.

Other objects and features of novelty are to provide a device that may be used on any 10 yarn machine, a device that will not require any additional effort or time of operator to thread it or outside power to operate it, and that will permit adjustment of tension so as to regulate the degree of cleaning or prevent 15 breaking of the yarn and to provide for means of cleaning a plurality of yarns at the same time.

This invention consists essentially of a cylindrically, or otherwise shaped, wire gauze 20 or netting of mesh and gauge suitable to the thickness and the grade of the yarn to be cleaned with other certain features of construction and arrangement of the several parts, to be hereinafter fully described, illustrated in the accompanying drawings and 25 specifically pointed out in the appended claims.

In describing my invention in detail, reference will be had to the accompanying 30 drawings wherein like characters denote like or corresponding parts throughout the several views, and in which:—

Figure 1 is an end view of the invention showing the same in use.

Figure 2 is a side view of the device.

Figure 3 is a section on line 3—3 of Figure 2.

Figure 4 is a fragmentary sectional view.

Figure 5 is a fragmentary view of a modification.

Figure 6 is a view of another modification.

Figure 7 is a section on line 7—7 of Figure 6.

In these views 1 indicates a bracket which 45 is supported from the traverse bar 2 by the U-bolt 3. A bolt 4 is carried by the bracket and the outer end of the bolt engages the bight of a yoke-shaped frame 5 which forms part of a cylindrical body 6. This body 50 supports a screen 7 by means of the ring 8 on the cleats 9. A floating bushing 10 is placed on the bolt, the same being limited in its movement by the spacer 11. A tubular member 12 is placed on the bushing, the inner end of said member entering a recess 13 formed in the bracket 1 and its outer end

having connected therewith the fan blades 14. A groove 15 is formed in the member outside the body 6.

The yarn coming from the bobbin, as 60 shown in Figure 1, is placed over the tubular member 12 so that it will engage the V-shaped groove 15 therein and it is then passed around the screen and then connected with the spool. Thus as the yarn passes 65 over the portions of the screen the particles of sand, seed, shell, bunches and slubs are cut off and the yarn becomes clean and even. The yarn passing over the tubular member 70 will rotate the same so that the fan blades 75 will act to blow the foreign matter scraped off the yarn from the screen.

The screen as shown in the first form of the invention is formed of wire mesh but it 75 may be made of inclined bars spaced apart, as shown at 16 in Figure 5.

As will be seen the yarn is cleaned and the foreign matter taken therefrom is blown away and all this is performed without the use of outside power as the movement of the 80 yarn itself operates the fan.

Figures 6 and 7 show a device of considerable length so that a plurality of yarns may be cleaned at the same time and in this arrangement a blower 16' is connected with 85 a perforated tube 17 by the pipes 18 so that the air from the blower will be directed through the screen to clean the same, the perforations being arranged at points opposite the yarns. In this form the yarns 90 are first passed over hooks 19 on the device before being passed around the device.

I may also provide an adjustable cover 20 which is slidably mounted on the device by 95 having its end edges engaging the guideways 21, said cover being arranged to enclose portions of the screen and thus regulate the amount of cleaning surface engaged by the yarn. This cover regulates the degree of 100 cleaning and the tension applied to the yarn by the screening surface. The portion of the cover engaged by the yarn is smooth so as to offer the least resistance to the passage of the yarn over the same. This arrangement is shown in connection with 105 both forms of the invention, as will be seen from an inspection of Figures 1, 2 and 4 and also Figures 6 and 7.

I may use different means for cleaning the 110 screening surface other than an air blast. For instance, I may use vacuum means or brush means.

In some cases it may be desirable to move the screen so that the yarn is moving over a moving cleaning surface which will increase the cleaning effect. The drawing shows a simple means of moving the screen longitudinally which consists of an eccentric 22 which is connected with the device by the link 23 so that when the shaft 24 is rotated the screen will be reciprocated. The screen is prevented from rotating on the pipe 17 while it is being reciprocated through means of the key 25.

It is thought from the foregoing description that the advantages and novel features 15 of my invention will be readily apparent.

I desire it to be understood that I may make changes in the construction and in the combination and arrangement of the several parts, provided that such changes fall within 20 in the scope of the appended claims.

What I claim is:—

1. A yarn cleaning device comprising a screen-like surface formed of spaced wires over which the yarn passes on its way to its 25 holder, means for cleaning the surface of matter removed from the yarn, such cleaning means consisting of a fan actuated by the movement of the yarn.

2. A yarn cleaning device comprising a

screen-like surface formed of spaced wires 30 over which the yarn passes on its way to the spool, adjustable means for regulating the amount of cleaning surface engaged by the yarn, such adjustable means consisting of a sliding cover having a smooth surface which 35 is engaged by the yarn.

3. A yarn cleaning device of the class described comprising a screen-like surface formed of spaced wires over which the yarn passes on its way to the spool, a fan for 40 cleaning the surface and means for actuating the fan by the movement of the yarn.

4. A yarn cleaning device of the class described comprising a screen formed of wire mesh over which the yarn passes on its way 45 to the spool, a fan actuated by the moving yarn for blowing the material scraped from the yarn by the screen from the screen.

5. A yarn cleaner of the class described comprising a cylindrical body having a 50 screen part formed of wire mesh, guiding means for causing the yarn on its way to the spool to pass around the screen part at an angle thereto, a fan within the cylindrical body and means for actuating the same by 55 the movement of the yarn.

In testimony whereof I affix my signature.
VINCENT WAITKUS.
